UNITED STATES PATENT OFFICE.

GEORGE BROWNING, OF WILMETTE, ILLINOIS, ASSIGNOR TO CHICAGO FLEXIBLE SHAFT COMPANY, OF CHICAGO, ILLINOIS, A CORPORATION OF ILLINOIS.

DESIGN FOR A COMBINATION PLUG AND SWITCH FOR ELECTRICAL APPLIANCES.

Application filed February 5, 1927. Serial No. 20,629. Term of patent 14 years.

To all whom it may concern:

Be it known that I, GEORGE BROWNING, a citizen of the United States, residing in the city of Wilmette, in the County of Cook, in the State of Illinois, have invented a new, original, and ornamental Design for a Combination Plug and Switch for Electrical Appliances, of which the following is a specification, reference being had to the accompanying drawings, forming a part thereof.

In the drawing:

Figure 1 is a perspective view of a com-

bination plug and switch embodying my new design.

Figure 2 is a front elevation of the same.

Figure 3 is a side elevation.

I claim:

The ornamental design for a combination plug and switch for electrical appliances substantially as shown.

In testimony whereof, I have hereunto set my hand this 3rd day of February, 1927.

GEORGE BROWNING.
